UNITED STATES PATENT OFFICE.

HORACE W. HACKER, OF CHICAGO, ILLINOIS, ASSIGNOR TO HACKER MANUFACTURING CO., OF CHICAGO, ILLINOIS, A CORPORATION OF ILLINOIS.

PRINTING PRESS.

Application filed January 14, 1924. Serial No. 686,071.

To all whom it may concern:

Be it known that I, HORACE W. HACKER, citizen of the United States, residing at Chicago, in the county of Cook and State of Illinois, have invented a certain new and useful Improvement in Printing Presses, of which the following is a full, clear, concise, and exact description.

My invention relates to printing presses employing cooperating printing members with which bearers are assembled that cooperate in the printing and with which printing press members intermeshing gear elements are assembled to cause the restoration 15 of the printing press members to non-printing positions after the printing operation.

The invention has for its object the provision of means whereby the gear elements 20 are prevented from disturbing the cooperative relation of the bearers in the printing operation, whereby "slurring" is avoided. This difficulty was due to the non-uniformity in the spacing of the sides of the gear 25 teeth that have meshing engagement during the printing operation, this non-uniformity obviously causing slippage between the functioning bearers with the attendant "slurring."

30 In carrying out my invention I permit one of the gear elements to move whenever any irregularity in the gear teeth spacing is encountered during the printing operation.

35 My invention has been of particular service in connection with presses employing flat beds and cooperating printing cylinders, one such member of a press being provided with a bearer that serves to operate the complementary bearer and the printing press member coupled with the latter. Mechanism is employed for bringing these bearers into and out of cooperating relation. A spur gear may be coupled with the cylinder to be 40 coaxial therewith and a complementary rack, in mesh with this gear, may be carried by the bed. This rack is desirably formed in two sections, one substantially in fixed connection with the bed and in mesh during 45 the non-printing stroke preferably by being arranged along the nonprinting area of the bed, and the other being assembled with the bed to be movable during the printing stroke preferably by being arranged along 50 the printing area thereof. The fixed mem-

ber of the rack serves to bring the members of the press into exact predetermined relation at the commencement of the actual printing operation. During the printing, the movable rack section permits the bearers 60 to remain in firm and non-slipping engagement. After the printing operation, the bearers are separated and the movable rack section then functions to move the bed in a nonprinting stroke, the fixed rack section 65 completing the nonprinting stroke of the bed. When the movable rack section is out of mesh with the gear upon the cylinder a spring or other means serves to move it in a normal intertoothed relation with the fixed 70 rack section, this spring permitting the movement of the movable rack section during the printing stroke for the purpose set forth.

The invention will be more fully explained in connection with the accompanying drawings in which Fig. 1 is a side view, with parts broken away, illustrating a proof press equipped in accordance with my invention, the bearers being in engagement 75 preparatory to the printing operation to ensue during the movement of the bed to the right as illustrated in this figure; Fig. 2 is a plan view of the bed portion of the press with parts broken away; Fig. 3 is an 80 enlarged side view on line 3-3 of Fig. 2; Fig. 4 is a view similar to Fig. 1 but illustrating the press at the conclusion of the printing stroke and with the bearers separated preparatory to the nonprinting stroke 85 of the bed; and Fig. 5 is a sectional view on line 5-5 of Fig. 1.

Like parts are indicated by similar characters of reference throughout the different figures.

In the press illustrated, one member is in the form of a cylinder 1 and a complementary member is in the form of a flat bed 2 though it is to be understood that the invention is not to be limited to any particular form of 100 press. The flat bed 2 may contain a printing form as illustrated at 3 in Figs. 2 and 5. The cylinder 1 is provided with a pair of bearers 4, one at each end of the cylinder. Complementary bearers 5 are provided upon 105 the flat bed. Mechanism is employed for bringing the bearers 4 into and out of engagement with their complements 5. In the proof press illustrated, this mechanism is operated by the hand crank 7 which is em- 110

ployed to turn the printing cylinder 1. As illustrated most clearly in Fig. 5, the crank shaft 8 carries a collar 9 fixed thereon. This collar has a tooth 9' which is engageable with a tooth 10' of the collar 10 loose upon the shaft 8. The collar 10 has another tooth 10² which is engageable with the tooth 11' upon the collar 11 loose upon the shaft. While the crank is being turned about three and one half times in one direction to print, or in the opposite direction to restore the printing press to nonprinting positions, the collars 9, 10 and 11 are being brought into relation to operate a crank 12 carried upon the collar 11. The crank 12 is, during this interval, thus operated to swing the rocker arm 13 in one direction or the other according to the direction of movement of the crank 7. The rocker arm 13 is connected with another rocker arm 14 by means of a link 15. A link 16 joins the rocker arm 14 with the cranks 17. Thus, when the arm 13 is moved in the manner described, the arm 14 and the cranks 17 are moved simultaneously therewith. Each of the elements 13 and 17 is carried upon one of the three shafts 18 individual thereto, each shaft being journaled at its ends in the bearings 19, as illustrated most clearly in Fig. 5. Each shaft 18 carries a cylindrical eccentric 20 upon which a roller 21 is journaled. The three rollers 21 carry the bed which has rail portions 22 bearing upon the annular flange portions 23 of the rollers. When the cylinder is in that portion of its turning movement which completes the movement of the bed in its printing direction, the collars 9, 10 and 11 co-operate to extend the crowns of the eccentrics horizontally whereby the bed is lowered and the bearers are separated, Fig. 4. When the bed is in the final portion of its nonprinting stroke, due to the reversed rotation of the printing cylinder, the collars 9, 10 and 11 again co-operate to adjust the eccentrics which are consequently placed with their crowns uppermost, to raise the bed and engage the bearers. The bed and cylinder are geared together in order that the bed may be moved in a nonprinting direction and may be adjusted to a fixed point at the commencement of the printing operation which is to be effected by the cooperation of the bearers. The gearing illustrated for this purpose includes a spur gear 24 fixed upon and coaxial with the printing cylinder 1 and a rack assembled with the bed and comprising two aligned sections 25 and 26 placed along the bed and each adapted to have meshing engagement with the spur gear. The section 26 is held in fixed relation with the bed by the bolts 27, this rack section 26 being located along the nonprinting area of the bed. The bolts 27 are screwed into the rack section 25 and serve

to hold this rack section against the top face of the bed. The shanks of the bolts 27 pass through elongated openings 28 in the bed, whereby the rack section 25 is permitted to move along the bed at the printing area thereof. A pin 29 is carried by the rack section 25 and is in sliding engagement with the adjacent end of the rack section 26. A coiled spring 30 is housed within the rack section 26 and presses upon the pin 29 which has a shoulder engaging the rack section 25 whereby the spring is enabled to move the rack section 25 to bring its teeth into proper intertoothed relation with the teeth of the rack section 26, the movement effected by the spring being limited by the abutment 25'. This result occurs when the rack section 25 is moved out of mesh with the gear 24 in the nonprinting stroke. The form having been inked by any suitable inking mechanism, such as that indicated at 31 in Fig. 1, the bed is moved to the right in its printing stroke, the fixed rack section 26 establishing a predetermined relative position of the bearers when the gear 24 leaves the rack section 26 and enters into engagement with the movable rack section 25. Some slight sliding movement of one set of bearers upon the other may occur while the gear 24 is in mesh with the rack section 26 but inasmuch as this rack portion is not coextensive with any portion of the printing area, the slippage between the two sets of bearers during this portion of the operation of the press causes no harmful results. The fixed rack section in conjunction with the spring 30, establishes a definite location for the commencement of the printing operation, the spring positioning the rack section 25 against the abutment 25'. The two sets of complementary bearers, being now in engagement, cause the printing operation to ensue irrespective of the rack and gear, the rack section 25 moving as required to permit the bearers upon the cylinder to drive the bearers upon the bed without the aid or interference of the rack and gear. When the bed is finishing its printing stroke it is lowered, in a manner hitherto described, to break the printing couple between the cylinder and bed. When the bed has been thus lowered the now reversely rotated gear 24 causes a return stroke of the bed while the bearers are in separated relation. During the final portion of this stroke, the printing bed is raised in the manner described, preparatory to another printing operation.

It is obvious that changes may be made without departing from the spirit of my invention.

Having thus described my invention I claim as new and desire to secure by Letters Patent the following:—

1. In a printing press, the combination with the printing cylinder thereof; of a re-

8. In a printing press, the combination of the aforesaid printing press members and in mesh during the nonprinting stroke, and the other section being assembled with this printing press member to be movable and in mesh during the printing stroke; and a 70 spring for restoring the movable gear element section into normal relation with its complement when out of mesh.
9. In a printing press, the combination with one member thereof in the form of a printing cylinder; of a second member in the form of a reciprocable flat bed cooperating with the cylinder in printing; bearers upon the cylinder and bed, one serving to operate the other and the printing press member coupled with it, in the printing operation; mechanism for bringing said bearers into and out of cooperative relation; a gear element coupled with one member; a complementary gear element coupled with the other element and in the form of a rack in mesh with the aforesaid gear element, one of 15 said gear elements being formed in two sections, one section being substantially in fixed connection with one of the aforesaid printing press members and in mesh during the nonprinting stroke, and the other section 20 being assembled with this printing press member to be movable and in mesh during the printing stroke; and automatic means for restoring the movable gear element section into normal relation with its complement when out of mesh.
10. In a printing press, the combination with one member thereof in the form of a printing cylinder; of a second member in the form of a reciprocable flat bed cooperating with the cylinder in printing; bearers upon the cylinder and bed, one serving to operate the other and the printing press member coupled with it, in the printing operation; mechanism for bringing said bearers into and out of cooperative relation; a gear element coupled with one member; a complementary gear element coupled with the other member and in the form of a rack in mesh with the aforesaid gear element, one 30 of said gear elements being formed in two sections, one section being substantially in fixed connection with one of the aforesaid printing press members and in mesh during the nonprinting stroke, and the other section 35 being assembled with this printing press member to be movable and in mesh during the printing stroke; and means for restoring the movable gear element section into normal relation with its complement when out of mesh.
11. In a printing press, the combination with one member thereof in the form of a printing cylinder; of a second member in the form of a reciprocable flat bed cooperating with the cylinder in printing; bearers upon the cylinder and bed, one serving to operate the other and the printing press member coupled with it, in the printing operation; a gear element coupled with one member; a complementary gear element in the form of a rack coupled with the other member and in mesh with the aforesaid gear element, one of said gear elements being 40 formed in two sections, one section being substantially in fixed connection with one of the aforesaid printing press members and in mesh during the nonprinting stroke, and the other section being assembled with this printing press member to be movable and in mesh during the printing stroke; and automatic means for restoring the movable gear element section into normal relation with its complement when out of mesh.
12. In a printing press, the combination with one member thereof in the form of a printing cylinder; of a second member in the form of a reciprocable flat bed cooperating with the cylinder in printing; bearers upon the cylinder and bed, one serving to operate the other and the printing press member coupled with it, in the printing operation; a gear element coupled with one member; a complementary gear element in the form of a rack coupled with the other member and in mesh with the aforesaid gear element, one of said gear elements being 45 formed in two sections, one section being substantially in fixed connection with one of the aforesaid printing press members and in mesh during the nonprinting stroke, and the other section being assembled with this printing press member to be movable and in mesh during the printing stroke; and means for restoring the movable gear element section into normal relation with its complement when out of mesh.
13. In a printing press, the combination with two complementary printing members thereof; of bearers upon said press members, one serving to operate the other and the printing press member coupled with it, in the printing operation; mechanism for bringing said bearers into and out of cooperative relation; a gear element coupled with one member; a complementary gear element coupled with the other member and in 50 mesh with the aforesaid gear element, one 55

of said gear elements being formed in two sections, one section being substantially in fixed connection with one of the aforesaid printing press members and in mesh during the nonprinting stroke, and the other section being assembled with this printing press member to be movable and in mesh during the printing stroke; and a spring for restoring the movable gear element section into normal relation with its complement when out of mesh.

14. In a printing press, the combination with two complemental printing members thereof; of bearers upon said press members, one serving to operate the other and the printing press member coupled with it, in the printing operation; mechanism for bringing said bearers into and out of co-operative relation; a gear element coupled with one member; a complemental gear element coupled with the other member and in mesh with the aforesaid gear element, one of said gear elements being formed in two sections one section being substantially in fixed connection with one of the aforesaid printing press members and in mesh during the nonprinting stroke, and the other section being assembled with this printing press member to be movable and in mesh during the printing stroke; and automatic means for restoring the movable gear element section into normal relation with its complement when out of mesh.

15. In a printing press, the combination
25 with two complemental printing members
thereof; of bearers upon said press members,
one serving to operate the other and
the printing press member coupled with it,
in the printing operation; mechanism for
40 bringing said bearers into and out of coop-
erative relation; a gear element coupled
with one member; a complemental gear ele-
ment coupled with the other member and in
45 mesh with the aforesaid gear element, one
of said gear elements being formed in two
sections, one section being substantially in
fixed connection with one of the aforesaid
printing press members and in mesh during
50 the nonprinting stroke, and the other sec-
tion being assembled with this printing
press member to be movable and in mesh
during the printing stroke; and means for
restoring the movable gear element section
55 into normal relation with its complement
when out of mesh.

16. In a printing press, the combination with two complementary printing members thereof; of bearers upon said press members, one serving to operate the other and the printing press member coupled with it in the printing operation; a gear element coupled with one member; a complementary gear element coupled with the other member and in mesh with the aforesaid gear element, one of said gear elements being

formed in two sections, one section being substantially in fixed connection with one of the aforesaid printing press members and in mesh during the nonprinting stroke, and the other section being assembled with this printing press member to be movable and in mesh during the printing stroke; and a spring for restoring the movable gear element section into normal relation with its complement when out of mesh. 75 70 75

17. In a printing press, the combination with two complementary printing members thereof, of bearers upon said press members, one serving to operate the other and the printing press member coupled with it, in the printing operation; a gear element coupled with one member; a complementary gear element coupled with the other member and in mesh with the aforesaid gear element, one of said gear elements being formed in two sections, one section being substantially in fixed connection with one of the aforesaid printing press members and in mesh during the nonprinting stroke, and the other section being assembled with this printing press member to be movable and in mesh during the printing stroke; and automatic means for restoring the movable gear element section into normal relation with its complement when out of mesh. 95

18. In a printing press, the combination with two complemental printing members thereof; of bearers upon said press members, one serving to operate the other and the printing press member coupled with it, in the printing operation; a gear element coupled with one member; a complemental gear element coupled with the other member and in mesh with the aforesaid gear element, one of said gear elements being formed in two sections, one section being substantially in fixed connection with one of the aforesaid printing press members and in mesh during the nonprinting stroke, and the other section being assembled with this printing press member to be movable and in mesh during the printing stroke; and means for restoring the movable gear element section into normal relation with its complement when out of mesh. 115

19. In a printing press, the combination with two complementary printing members thereof; of bearers upon said press members, one serving to operate the other and the printing press member coupled with it, 120 in the printing operation; a gear element coupled with one member; and a complementary gear element coupled with the other member and in mesh with the aforesaid gear element, one of said gear elements being 125 formed in two sections, one section being substantially in fixed connection with one of the aforesaid printing press members and in mesh during the nonprinting stroke, and the other section being assembled with this 130

printing press member to be movable and in mesh during the printing stroke.

20. In a printing press, the combination with two complemental printing members 5 thereof; of bearers upon said press members, one serving to operate the other and the printing press member coupled with it, in the printing operation; a gear element coupled with one member; and a comple-

mental gear element coupled with the other 10 member and in mesh with the aforesaid gear element during the printing stroke and movable while in mesh.

In witness whereof, I hereunto subscribe my name this 9th day of January, A. D. 15 1924.

HORACE W. HACKER.
